UNITED STATES PATENT OFFICE.

BAINBRIDGE W. BURDICK, OF ALBANY, NEW YORK.

DESIGN FOR A SWING-COVER-CATCH SHELL.

SPECIFICATION forming part of Design No. 30,781, dated May 16, 1899.

Application filed May 25, 1898. Serial No. 681,747. Term of patent 14 years.

To all whom it may concern:

Be it known that I, BAINBRIDGE W. BURDICK, a citizen of the United States, residing at Albany, in the county of Albany and State of New York, have invented and produced a new and original Design for Swing-Cover-Catch Shells, of which the following is a specification, reference being had to the accompanying drawings, forming a part thereof.

Figure 1 is a perspective view of a swing-cover-catch shell, showing my new design, viewed from its rear side and open end. Fig. 2 is a perspective view of the same from its rear side and partly-open end. Fig. 3 is a perspective view of the same from its front side and open end.

As shown in the drawings, the leading and material features of my design consist in a swing-cover-catch shell having the shape or configuration comprising a circular wall portion A, which comprises in its extension of circumference about three-quarters of a cir-

cle and joins at its terminal lines a with plain flat wall portions a' and a'' , so as to jointly inclose a circular-form chamber B, Figs. 1 and 3, and a rectangular-form chamber B', communicating with each other, as shown in Fig. 1. One end of this shell is shown in Fig. 2 to have a closing-wall C, which is perforated with the oblong perforation c, which opens to the circular chamber B, while the opposite end has its circular chamber B left open or uncovered, while the rectangular chamber B' is shown to be covered by wall portion C'.

Having described my invention, what I claim as new, and desire to secure by Letters Patent, is—

The design for a swing-cover-catch shell, as herein shown and described.

BAINBRIDGE W. BURDICK.
